UNITED STATES PATENT OFFICE.

EDWIN F. HULBERT, OF MILWAUKEE, WISCONSIN, ASSIGNOR TO MASTER PACKAGE CORPORATION, OF OWEN, WISCONSIN, A CORPORATION OF WISCONSIN.

CONTAINER.

Application filed December 29, 1922. Serial No. 609,686.

To all whom it may concern:

Be it known that I, EDWIN F. HULBERT, a citizen of the United States, and resident of Milwaukee, in the county of Milwaukee and State of Wisconsin, have invented new and useful Improvements in Containers, of which the following is a description, reference being had to the accompanying drawings, which are a part of this specification.

10 The invention relates to containers and more particularly to a reinforced fibre container.

The object of the invention is to provide a container for cheese, coffee, grain, fruits and other commodities, which may be easily produced and which has its heads reinforced by metal bands that also secure the heads to the sides of the cover or body of the container.

20 With the above and other objects in view the invention consists in the construction hereinafter set forth and all equivalents.

In the drawings: Fig. 1 is a perspective view of a container embodying the invention; Fig. 2 is a sectional view taken on a radial line through the cover of the box; Fig. 3 is a view similar to Fig. 2 with the parts partly assembled; Figs. 4 and 5 are detail views showing the manner of clamping the band.

The construction of the cover 6 and body portion 7 of the container or box are the same and the side of the cover is designed to fit over the side of the body portion to 35 complete the container.

The subject matter of the invention relates to the means employed for connecting the head to the side of the cover or body of the box and as such means are identical 40 for both the cover and the body of the box the cover alone has been shown in detail for the purpose of explaining the invention.

The sides of the cover, as well as the sides of the box, are composed of concentric fibre rings or tubes 8 and 9 made of one or more plies of fibre and secured together in any suitable manner, as by gluing. The outer ring or tube 9 is wider than the ring or tube 8 and extends beyond it to form a chime 10. The circular head 11, which may be made of one or more plies of fibre, fits within the chime 10 and seats on the outer edge 12 of the ring 8. This head may have a peripheral groove 13 formed therein.

The head 11 is clamped to the sides of the 55 cover, as well as the sides of the box, by a sheet metal chime ring 14 which is tightly clamped about the outer ring 9 and preferably has tongues or spurs 15 punched therein and pressed into said ring 9 to prevent any possibility of slippage between said ring 14 and the siding. The upper edge 16 of the ring 14 is bent around the chime 10 and forms a reinforced peripheral edge, the ring being preferably so bent or spun as to have 60 its turned-over edge brought into engagement with the head 11 so as to tightly clamp the peripheral edge of said head between the edge 12 of the ring 8 and the chime ring, and where the head is provided with the groove 13 a part of the turned-over edge 16 extends into this groove.

The chime ring 14 is preferably made of a strip of sheet metal whose ends 17 and 18 are preferably hooked together around 70 the side of either the cover or body, as shown in Fig. 4, and then bent down against the sides to form an interlocked joint 19, as shown in Fig. 5, the ring being then in the form shown in Fig. 3, with its upper edge 75 extending over the chime 10. Then the indentations are made in the ring to form the tongues 15 after which the upper edge of the ring is turned over, as shown in Fig. 2, and in doing this part of the chime 10 is 80 also bent over with the ring, as shown at 20 in Fig. 2.

Where the box is used for cheese one or more ventilating openings 21 are punched through the box. It will be noted that in 90 the construction above described the metal ring forms a strong reinforcement for the top and bottom of the box or container and that said container rests upon this ring when placed on a support.

I desire it to be understood that this invention is not to be limited to any specific form or arrangement of parts except in so far as such limitations are specified in the claims.

What I claim as my invention is:

1. In a container, the combination, with a circular head, of siding including concentric inner and outer rings secured together, the outer ring extending beyond the inner ring 105 to form a chime and the outer edge of the inner ring forming a seat for the head whose peripheral portion fits within said chime,

and a sheet metal chime ring clamped to the outer ring and extending over into clamping engagement with said head.

2. In a container, the combination, with a circular head, of siding including inner and outer rings of fibre secured together, the outer ring extending beyond the inner ring to form a chime within which the head fits and the outer edge of the inner ring forming a seat for the head, and a sheet metal chime ring clamped to the outer ring and extending over into clamping engagement with said head, said metal chime ring having indented portions engaging said siding.
3. In a container, the combination, with a circular head, of siding including concentric inner and outer rings of fibre secured together, the outer ring extending beyond the inner ring to form a chime within which the head fits and the outer edge of the inner ring forming a seat for the head, and a sheet metal chime ring clamped to the outer ring and extending over with the chime portion of said outer ring into clamping engagement with said head.

4. In a container, the combination, with a circular head, of siding including concentric inner and outer rings secured together, the outer ring extending beyond the inner ring to form a chime within which the head fits and the outer edge of the inner ring forming a seat for the head, a strip of sheet metal having its ends interlocked to form a chime ring clamped to the outer ring with its outer edge extending over into clamping engagement with said head.

5. In a container, the combination, with a circular head, of siding including concentric inner and outer rings secured together, the outer ring extending beyond the inner ring to form a chime and the outer edge of the inner ring forming a seat for the head whose peripheral portion fits within said chime, a sheet metal chime ring clamped to the outer ring and extending over into clamping engagement with said head, and means for preventing relative movement between said chime ring and siding.

EDWIN F. HULBERT.
